UNITED STATES PATENT OFFICE

IRVING A. DELINE, OF DENVER, COLORADO

CARTON FOR BABY CHICKS

Application filed January 11, 1932. Serial No. 585,925.

This invention relates to a container for articles of a nature that require ventilation, and is more particularly desirable for cartons to be used in shipping baby chicks.

5 The principal object of the invention is to provide means for holding filled cartons in spaced relation when piled so that the air can circulate between the individual cartons.

Another object of the invention is to provide 10 a separator for cartons of this type which can be quickly and easily inserted for use whenever desired.

In the following detailed description of the invention, reference is had to the accompanying drawing which forms a part hereof. 15 Like numerals refer to like parts in all views of the drawing and throughout the description.

In the drawing: 20 Fig. 1 is a perspective view illustrating the invention ready for use.

Fig. 2 illustrates two cartons piled one on the other, the lower carton being shown in section.

25 Fig. 3 is a detail view illustrating the spacer member.

The usual box or carton for shipping baby chicks comprises a container such as illustrated at 10, having a removable lid 11. The 30 lid is usually provided with a series of ventilation holes 12.

The present invention comprises a plug 13 formed of wood or other comparatively inexpensive and easily formed material. The 35 plug 13 is provided with a lower portion 14 of a diameter to fit snugly into one of the holes 12 with the upper portion of the plug projecting above the lid 11.

Any desired number of the plugs may be 40 employed. It has been found that if one of the plugs is placed at each corner of the lid,

they will efficiently separate the cartons when piled one upon the other. The plugs may be removed and discarded after the carton has been delivered so as to increase the ventilation space, if desired.

If the plugs are formed so that it is necessary to employ considerable force to force them into the holes 12, they will hold themselves in place without further treatment. If desired, however, they may be glued or cemented in place. If the box is provided with side ventilation openings such as indicated at 14, the plugs 13 may, if desired, be used in the sides and ends to prevent adjacent boxes from being placed so close together as to shut off vertical ventilation thru a mass of boxes.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. A container for baby chicks and the like comprising a box; a lid for said box, said lid containing perforations; and plugs in certain of said perforations and projecting above said lid.

2. A container for baby chicks and the like comprising a box; a lid for said box, said lid containing perforations; and plugs in certain of said perforations and projecting above said lid, said plugs having a relatively small diameter which passes through said perforation and relatively large diameter which rests upon the top of said lid.

In testimony whereof, I affix my signature.

IRVING A. DELINE.
